EDWARD P. JONES, OF SHELL MOUND, MISSISSIPPI.

Letters Patent No. 100,899, dated March 15, 1870.

IMPROVEMENT IN HASP AND STAPLE FASTENING.

The Schedule referred to in these Letters Patent and making part of the same

To all whom it may concern:

Be it known that I, EDWARD P. JONES, of Shell Mound Post Office, in the county of Sunflower, and State of Mississippi, have invented certain new and useful Improvements in Hasp and Staple Fastenings; and I do hereby declare that the following is a full, clear, and exact description of the same, reference being had to the accompanying drawing and to the letters of reference marked thereon making part of this specification, in which—

Figure 1 is a front view of my improved device applied to gate or door.

Figure 2 is a plan view of my improved device attached.

Figure 3 is a plan view of the staple and its fastener.

Figure 4 is a plan view of the eye-bolt and its fastener that secures the hasp.

The object of my present invention is to so secure the staple of the ordinary hasp fastening that additional security is afforded.

The nature of my invention consists in securing the staple in the post by means of a bearing-plate or nut.

The staple consists of an eye-bolt, having a screw-thread cut on its shank. The bearing-plate or nut is inserted through an opening cut, bored, or mortised in the post, at such point that the opening in the plate or nut can be conveniently brought in contact with the end of the staple-shank, and being provided with a female screw-thread, is easily secured, simply by turning the staple.

The eye of the staple is of such dimensions as to prevent its turning in the slot of the hasp, so that with my improvement, after the hasp is once secured by the lock, it is impossible to withdraw the staple, and consequently a positive security against depredations is afforded.

To enable others skilled in the art to make and use my invention, I will now proceed to describe its construction and operation.

A is the door or gate of the crib, out-house, or other building that it is desired to secure.

B B' are the posts, the door or gate being hinged to the post B', in the usual manner.

In the post B there is mortised, cut, or bored a horizontal opening, b. This opening b may be extended entirely through the post B, as shown in fig. 1, or only to such distance into the body of the post as to allow the eye of the screw-nut or plate it is intended to receive to be pushed opposite to the opening b', through which the shank of the staple is to be inserted.

C is the staple, and is constructed as shown in fig. 3, that is, with a single shank, c, and an eye, c¹.

On the shank c of this staple is cut a screw-thread, c². C' is a nut or bearing-plate, that secures the hasp after it has been inserted into the post B.

D is the hasp, and is constructed with an eye, d, and an oblong slot, D'. This hasp is secured to the door by an eye-bolt, E, which is constructed with a screw-threaded shank, e, and is fastened by a nut, E'.

The form of this bolt is clearly shown in fig. 4.

The operation is as follows:

In the post B is cut or bored the opening b. If this opening does not extend through the post, it must be made sufficiently deep to extend a short distance beyond the point at which it meets the opening b'. Through this opening b' is passed the shank of the staple C. The nut or plate C' is then inserted in the opening b, and pushed to such position that the end of the shank c shall enter the female screw of the nut or plate C'. Then simply, by turning the shank c, it can be fastened, and drawn so as to leave the lower face of the eye c¹ bearing against the post B. Care should be taken that the opening b and nut or plate C' are of such relative dimensions as to render it impossible for the latter to be revolved in the former. The eye-bolt E is inserted through an opening in the door or gate A, and is fastened by the nut E' on the inside. The hasp having been placed over the staple and secured by the lock F, it will be observed that the staple cannot be withdrawn unless it is revolved, and as the slot D securely prevents the turning of the eye c¹, access cannot be had except through a key or the breaking of the lock.

The device is readily applied, and when unlocked, can easily be removed.

Having thus fully described my invention, What I claim therein as new, and desire to secure by Letters Patent of the United States, is—

Securing the staple C by means of a nut or plate, C', when the post to which it is to be attached has openings b b' cut, bored, or mortised in the same, substantially as described.

In testimony whereof I have signed my name to this specification in the presence of two subscribing witnesses.

EDWD. P. JONES.
